UNITED STATES PATENT OFFICE

JAMES H. RAND, JR., AND JOHN A. ZELLERS, OF BUFFALO, NEW YORK, ASSIGNORS TO
REMINGTON RAND INC., OF NEW YORK, N. Y., A CORPORATION OF DELAWARE

DESIGN FOR A TOP OR COVER PLATE FOR TYPEWRITING MACHINES

Application filed December 29, 1932. Serial No. 46,654. Term of patent 3½ years.

To all whom it may concern:

Be it known that we, JAMES H. RAND, JR. and JOHN A. ZELLERS, citizens of the United States, residing at Buffalo, in the county of Erie and State of New York, have jointly invented a new, original, and ornamental Design for a Top or Cover Plate for Typewriting Machines, of which the following is a specification, reference being had to the accompanying drawings, forming a part thereof.

Fig. 1 is a perspective view of a top or

cover plate for typewriting machines showing our design.

Fig. 2 is a top plan view of the same.

Fig. 3 is an end view of the same.

We claim:

The ornamental design for a top or cover plate for a typewriting machine as shown.

Signed at Buffalo, in the county of Erie and State of New York, this 19 day of Dec., 1932.

JAMES H. RAND, JR.
JOHN A. ZELLERS.
